UNITED STATES PATENT OFFICE.

ALBERT GATES, OF YUMA, ARIZONA TERRITORY.

WASHING-MACHINE.

No. 918,995.

Specification of Letters Patent.

Patented April 20, 1909.

Application filed September 25, 1908. Serial No. 454,717.

To all whom it may concern:

Be it known that I, ALBERT GATES, a citizen of the United States, residing at Yuma, in the county of Yuma and Territory of 5 Arizona, have invented new and useful Improvements in Washing-Machines, of which the following is a specification.

This invention relates to improvements in washing machines, the object of the invention 10 being to provide a washing machine embodying compressors whereby the washing of the clothes is accomplished by the forcible expression of the suds water through the fabric, and also embodying a novel mode of mounting 15 the compressors and arrangement of means for operating the same, whereby great compressing power may be secured with the application of comparatively little strength on the part of the operator.

20 The invention consists of the features of construction, combination and arrangement of parts hereinafter fully described and claimed, reference being had to the accompanying drawing, in which:—

25 Figure 1 is a vertical longitudinal section through a washing machine embodying my invention. Fig. 2 is a vertical transverse section of the same.

The apparatus embodies a tub or vessel 1, 30 preferably of oblong rectangular form, and having a plane or flat bottom 2. Secured crosswise of the middle of said bottom 2 is a transverse bar or cleat 5, to the opposite sides of which are hinged or pivoted, as at 6, a pair 35 of swinging compression devices 7 and 8 movable toward and from the bottom to cooperate therewith in forcing the water through the clothes. The said compressing devices 7 and 8 preferably consist of blocks of 40 suitable size and weight and are provided with a flat or plane bottom surface to bear squarely upon the clothes. Pivoted mounted at its lower end, as at 9, to the upper surface of the bar 5 between the compression blocks is an 45 oscillating lever 10, the upper end of which projects a suitable distance above the vessel or tub and is formed to provide an operating handle 11. The lever is connected to the outer sides of longitudinal ribs or flanges 7' 50 and 8' on the compression blocks by links 12 and 13, each of which is hinged or pivoted at its inner end to the lever, as at 14, and

hinged or pivoted at its outer end to the co-acting block, as at 15. These links preferably consist of rigid bars, so that the pressure 55 applied to the lever may be directly transmitted to the blocks.

In operation, the vessel or tub is supplied with a proper quantity of suds water and the clothes inserted therein so as to lie between the bottom 2 and the coöperating compression blocks 7 and 8, and the lever 10 is oscillated back and forth to alternately depress and elevate the compression blocks. Each block in operation is forced squarely 60 down against the clothes lying between the same and the adjacent surface of the bottom and forces the water through the clothes, thus dislodging and carrying off the dirt, whereby the clothes are cleansed. Owing to 65 this mode of washing the clothes, wear and tear upon the clothes is avoided, and as, in addition to the pressure from the weight of the blocks the full strength of the operator may be exerted through the action of the 70 lever and the connecting link, it is apparent that great pressure may be applied, even at the expenditure of comparatively little strength on the part of the operator, to forcibly 75 drive the water through the clothes.

A washing machine constructed in accordance with my invention is simple, cheap, efficient and durable, and enables a large amount of clothes to be washed within a comparatively short time.

Having thus fully described the invention, what is claimed as new is:—

1. A washing machine comprising a tub or vessel, a pair of pivotally mounted compressors arranged therein, an operating lever 90 arranged between said compressors, and links pivotally connecting said lever with said compressors.

2. A washing machine comprising a tub or vessel having a flat bottom, a cross bar secured to the bottom, compressor blocks pivoted to the opposite sides of the bar for movement toward and from the bottom, an oscillating lever pivoted to the bar, and links connecting said lever with said compressing 95 blocks.

3. A washing machine comprising an oblong rectangular tub or vessel having a flat bottom, a cross bar secured to the bottom,

compression blocks pivotally mounted upon the bar for movement toward and from the bottom, a lever pivotally mounted upon the bar between said compression blocks, and 5 rigid links pivotally connecting said lever with the outer ends of the compression blocks.

In testimony whereof I affix my signature in presence of two witnesses.

ALBERT GATES.
